(57) **CLAIM**

The ornamental design for a pump for inflatable bladder, as
shown and described.

DESCRIPTION

FIG. 1 is a front isometric view of the pump illustrating top
environment;

FIG. 2 is a front side view of the pump of FIG. 1 illustrating
top and bottom environment;

FIG. 3 is another front isometric view of the pump of FIG. 1
without illustrating environment;

FIG. 4 is a front side view of the pump of FIG. 2;

FIG. 5 is a right side view of the pump of FIG. 2;

FIG. 6 is a rear side view of the pump of FIG. 2;

FIG. 7 is a left side view of the pump of FIG. 2;

FIG. 8 is a top side view of the pump of FIG. 2; and,

FIG. 9 is a bottom side view of the pump of FIG. 2.

The broken lines immediately adjacent the shaded areas
represent the bounds of the claimed design while all other broken
lines are directed to environment and are for illustrative pur-
poses only; the broken lines form no part of the claimed
design.
